United States Patent Office.

CHARLES F. WALKER, OF BENFORD'S STORE POST OFFICE, PENNSYLVANIA.

Letters Patent No. 93,255, dated August 3, 1869.

IMPROVED WASHING-MACHINE.

The Schedule referred to in these Letters Patent and making part of the same.

To all whom it may concern:

Be it known that I, CHARLES F. WALKER, of Benford's Store Post Office, in the county of Somerset, and State of Pennsylvania, have invented new and useful Improvements on a certain Washing-Machine, for which Letters Patent were granted to me, bearing date the 5th day of March, 1867, No. 62,708; and I do hereby declare that the following is a full, clear, and exact description of the construction and operation of the same, reference being had to the accompanying drawings, making a part of this specification, in which—

Figure 1 is a perspective view of my box-machine as improved.

Figure 2, the same applied or used in a common washing-tub.

Figure 3, the dashers, &c., detached or shown separately, showing the bevel-edged pieces L and the entire cross-strips or uniting-link G.

The object of this invention is to produce a cheap, simple, and easily-adjusted and regulated washer, to which end certain details of construction are employed, which will be more fully described hereinafter.

To enable others skilled in the art to make and use my invention, I will proceed to describe the same as introduced and modified.

B B represent two dashers, which may be made semicircular in form to fit an ordinary tub, or of any desired shape. They are connected by the link G, in such manner that each one is allowed a vertical motion independently of the other.

H H are vertical rods rigidly attached to the cross-bars L L on the dasher, which rods are attached, at their upper ends, to the lever C.

K is a transverse bar or strip, which is firmly attached to the top of the tub or receptacle containing the mechanism.

To the centre of the bar K is suitably attached the rope E, which passes through an orifice in the lever C, and is attached to a handle, F, above the same.

It will be seen that the rope E holds the lever C in position, and that the latter, when raised and lowered, imparts vertical motion alternately to each dasher.

The arrangement is regulated for different quantities of fabric by twisting or untwisting the rope E, which is accomplished by means of the handle F. The effect of the former operation will be to depress the lever C and its attachments, while the latter raises the same.

I am aware that two dashers arranged to receive alternate vertical motion are not new, nor do I claim the idea in itself; but

What I do claim, and desire to secure by Letters Patent, is—

In a washing-machine of the described construction, the handle F, rope E, and bar K, in combination with the lever C and its attachments, as and for the purpose set forth.

C. F. WALKER.
